(57) **CLAIM**

What is claimed is the ornamental design for a picture frame and easel, as shown and described.

DESCRIPTION

FIG. 1 is a perspective view of an picture frame and easel, showing the new design;

FIG. 2 is an exploded perspective view thereof, illustrating a frame portion and an easel portion;

FIG. 3 is a front elevational view of the easel portion;

FIG. 4 is a rear elevational view thereof;

FIG. 5 is a rear perspective view of the design;

FIG. 6 is a right-side elevational view of the easel portion, the left-side elevational view being a mirror image thereof;

FIG. 7 is a top plan view thereof;

FIG. 8 is a bottom plan view thereof;

FIG. 9 is a front elevational view of the frame portion;

FIG. 10 is a rear elevational view thereof;

FIG. 11 is a left-side elevational view of the easel portion, the right-side elevational view being a mirror image thereof;

FIG. 12 is a top plan view thereof, the bottom plan view being a mirror image thereof; and,

FIG. 13 is a rear perspective view thereof.

The broken lines showing artwork in FIG. 1 and suction cups in FIG. 13 are included for the purpose of illustrating the invention in use, and form no part of the claimed design.
